CLAIM

The ornamental design of a protective goggle, as shown and described.

DESCRIPTION

FIG. 1 is a front perspective view of a protective goggle showing a first embodiment of our new design;

FIG. 2 is a top plan view thereof;

FIG. 3 is a front elevation view thereof;

FIG. 4 is a right side elevation view thereof; the left side being identical to FIG. 4;

FIG. 5 is a rear elevation view thereof;

FIG. 6 is a bottom view thereof;

FIG. 7 is a front perspective view of a protective goggle showing a second embodiment of our new design;

FIG. 8 is a top plan view thereof;

FIG. 9 is a front elevation view thereof;

FIG. 10 is a right side elevation view thereof, the left side view being identical to FIG. 10;

FIG. 11 is a rear elevation view thereof; and,

FIG. 12 is a bottom plan view thereof.
